UNITED STATES PATENT OFFICE.

ALFRED G. F. KUROWSKI, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,067,664.

Specification of Letters Patent.

Patented July 15, 1913.

Application filed June 22, 1912. Serial No. 705,166.

To all whom it may concern:

Be it known that I, ALFRED G. F. KUROWSKI, a citizen of the United States, residing in Brooklyn borough, in the county of Kings and State of New York, have invented certain new and useful Improvements in Type-Writing Machines, of which the following is a specification.

This invention relates to the ribbon mechanism of typewriting machines.

In the usual forms of typewriting machines, when the platen is shifted to the upper case, the portion of the ribbon which covers the printing point is shifted so as to preserve its proper position relatively to the platen, the ribbon being paid out from the supply spool during the shifting. The result is that when the carriage returns to the lower case there is a certain amount of slack in the ribbon which is liable to smudge the paper, and prove otherwise objectionable.

The object of this invention is to overcome this difficulty, and to this end I connect to the lift rail frame a pawl which engages the ribbon-winding ratchet. When the lift rail frame is shifted for upper case, the pawl rides freely over the ratchet teeth, and, when the frame is returned to lower case, the pawl engages the ratchet so as to give it a partial turn which is sufficient to remove the slack created in the ribbon by the shift for upper case.

In the accompanying drawings, Figure 1 is an elevation view illustrating diagrammatically an Underwood writing machine with my invention applied thereto. Fig. 2 is a view similar to Fig. 1, illustrating the carriage and ribbon shifted to the upper case, and in position to receive the type impression. Fig. 3 is a perspective detail, illustrating the pawl and its connection to the lift rail frame. Fig. 4 is a detail illustrating the shifting of the ribbon.

The case shift key 1 has an arm 2 engaging the lift rail frame 3, which carries the lift rail 4 adapted to shift the platen to the upper case by engaging a roller 5 mounted on a bracket 6 fixed to the platen frame 7. The ribbon 3 is wound on spools 9, which are rotated by the ribbon feed ratchet 22 and intermediate gearing to feed the ribbon. The ratchet 22 is given a step-by-step rotation during the letter feed of the carriage by the pawls 22^a (Fig. 2) actuated by the usual mechanism. The ribbon is guided by

a ribbon guide or vibrator 10 connected to a lever 11 fulcrumed on a bracket 12 fixed to the lift rail. When the case shift key is depressed to shift the lift rail to the upper case the latter also lifts the lever 11 and vibrator to elevate the ribbon. When a type key is depressed, a type bar 13, with its heel 14, engages the universal bar 15 to shift the frame 16; which, through bracket 17, operates the lever 11 and vibrator 10 to further move the ribbon into position to cover the printing point. As illustrated in Figs. 2 and 4, this total movement of the ribbon is considerable, which produces a slack at the ribbon guide when the platen frame returns to the lower case. To take up this slack as soon as the carriage returns to the lower case, the lift rail frame 3 has connected thereto a link 18 which operates a slide 19 guided by pins 20 fixed to a bracket 21 mounted at any convenient point on the machine frame adjacent to the ribbon feed ratchet 22. Mounted on the slide 19, is a pawl 23 engaging the ratchet 22. This pawl may be formed with a projection 24 engaging the lower surface of a flange 24^a (Fig. 3) formed on the machine frame, which limits the upward movement of the pawl and avoids the possibility of its being thrown out of position should the ratchet accidentally be shifted laterally too far. A spring 25 mounted on the slide holds the pawl yieldingly against the teeth of the ratchet. When the carriage is shifted to the upper case, the pawl is moved forward and rides freely over the ratchet teeth, while when the carriage is returned the pawl gives the ratchet a partial rotation which takes up all the slack that has been formed.

Many variations may be resorted to within the scope of this invention. I do not desire to be limited therefore to the construction shown.

Having thus described my invention, I claim:

1. In a typewriting machine, the combination of a shiftable carriage, ribbon mechanism, and means for taking up the slack formed in the ribbon when the carriage is shifted to the upper case.

2. In a typewriting machine, a ribbon feed ratchet, case-shifting mechanism, and means for operating the ratchet from the case-shifting mechanism.

3. In a typewriting machine, a case shift key, a lift rail frame operated thereby, a

ribbon feed ratchet, and means for operating said ratchet from the lift rail frame.

4. In a typewriting machine, case shifting mechanism, ribbon actuating mechanism, and means for operating said ribbon actuating mechanism from the case-shifting mechanism.

5. In a typewriting machine, a ribbon feed ratchet, a lift rail frame, a link connected thereto, a slide connected to the link, and a pawl mounted on the slide engaging the ratchet.

6. In a typewriting machine, a ribbon feed ratchet, a lift rail frame, a link connected thereto, a slide connected to the link, a pawl mounted on the slide engaging the ratchet, and a projection on the pawl for limiting the lateral movement thereof.

7. In a typewriting machine, a ribbon feed ratchet, a lift rail frame, a link connected thereto, a slide connected to the link, a pawl mounted on the slide engaging the ratchet, and a spring for yieldingly holding the pawl in engagement with the ratchet.

8. In a typewriting machine, a ribbon feed ratchet, a lift rail frame, a link connected thereto, a slide connected to the link, a pawl mounted on the slide engaging the ratchet, a projection on the pawl, and a flange on the machine frame extending over said projection.

9. The combination with a case-shifting mechanism and an ink ribbon connected to shift with said case-shifting mechanism in a manner to produce a slack in the ribbon, of means connected to said case-shifting mechanism to operate upon the return thereof, for feeding the ribbon longitudinally to take up such slack.

10. In a typewriting machine, the combination with a pair of ribbon spools, of a vertically shiftable platen, a ribbon vibrator shiftable with the platen and thereby increasing the length of ribbon between the spools and vibrator when the platen is shifted to upper case position, and means to automatically take up the slack in the ribbon as the platen is lowered.

11. In a typewriting machine, the combination with a shiftable traveling carriage, of a ribbon vibrator shiftable with the carriage, a ribbon spool, a ribbon feed ratchet geared to the spool, mechanism to rotate said ratchet during the letter feed travel of the carriage, a pawl for said ratchet, and means to operate said pawl when the carriage is returned from shifted position, and thereby take up slack in the ribbon.
